(57) **CLAIM**

The ornamental design for an intelligent communication terminal, as shown and described.

DESCRIPTION

FIG. 1 is a perspective view of an intelligent communication terminal showing my new design;

FIG. 2 is another perspective view seen from the back side thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a partial, enlarged perspective view showing side keys thereof, as designated by label 9 in FIG. 1; and,

FIG. 10 is an enlarged partial perspective view showing left lateral part thereof, as designated by label 10 in FIG. 2.

The broken lines are for illustrating unclaimed portions of the intelligent communication terminal or environmental structures, which form no part of the claimed design.
